UNITED STATES PATENT OFFICE.

CHARLES F. RITCHEL AND JEREMIAH STEVER, OF BRIDGEPORT, CONNECTICUT, ASSIGNEES, BY DIRECT AND MESNE ASSIGNMENTS, TO S. S. AND G. D. TALLMAN, OF NEW YORK, N. Y.

TOY LOCOMOTIVE.

SPECIFICATION forming part of Letters Patent No. 267,939, dated November 21, 1882.

Application filed September 8, 1882. (No model.)

To all whom it may concern:

Be it known that we, CHARLES F. RITCHEL and JEREMIAH STEVER, both citizens of the United States, and residents of Bridgeport, 5 in the county of Fairfield and State of Connecticut, have invented new and useful Improvements in Toy Locomotives and other Carriages, of which the following is a specification.

10 Our invention consists of an improved spring motive power for toy carriages, and which is also useful for other purposes; and it also consists of an improved brake-regulator for the spring-power.

15 The objects are to simplify the power apparatus for toy carriages and lessen the liability of damage to the working parts; also, and especially, to provide a simpler and easier method of winding up the spring. The common 20 spring-powers, that wind up with a key applied to the shaft to which the spring is connected, are very hard to wind, and cannot well be managed by young children. These defects are remedied by this invention, as 25 hereinafter more fully described, reference being made to the accompanying drawings, in which—

Figure 1 is a longitudinal sectional elevation of part of a toy locomotive constructed 30 according to our invention, and Fig. 2 is a detail.

We make the shaft *a*, to which the inner 35 end of the driving-spring *b* is attached, to rest immovably in its fastenings *c*, and we make the outer periphery, *d*, of the spring-barrel to form a winding-drum, whereon we wind a 40 cord or chain, *e*, in such direction that by pulling the cord off from the drum and revolving it thereby it will coil up the spring and set it in tension for work. When the cord is wound up on the barrel, and while the spring is in an 45 extended condition, we connect it to the driving-axle *f* of the locomotive or other vehicle or machine to be driven, and by the use of the wheels *g* of said axle for a crank wind up the spring and set it in tension for work by winding the cord off from the drum onto the axle. When so wound up, set on the floor, and the

driving-wheels set free, the recoil of the spring will set the machine in motion. 50

The wheels *g* may have a crank-pin, *h*, to be taken in the hand, or for the application of a crank, *i*.

It will be seen that by this method of construction the winding of the spring is made 55 much easier by reason of the greater leverage afforded to the operator, although it may not be done as quickly.

The ratchet mechanism necessarily employed in the common arrangement for holding the 60 spring is dispensed with, because of the ease with which it may be held by the driving-wheels until set to work, and by the direct connection of the spring-barrel with the axle by a cord the mechanism is considerably simplified. 65 A train of gears may be used for this connection; but the cord is obviously the simplest and cheapest.

For the regulating-brake to control the speed of the machine, we propose to use springs to 70 bear on the axle or on collars thereon, and we prefer coiled springs *j*, arranged, as shown, with one end bearing on the axle and the other end bearing against the body of the vehicle or other suitable part. 75

Although we have represented a toy locomotive as the object to which our improved propelling mechanism is applied, we do not limit ourselves to that form of carriage, but may use it for baby-carriages, velocipedes, and other 80 forms of vehicles.

Having thus described our invention, what we claim, and desire to secure by Letters Patent, is—

1. The combination, with a toy locomotive 85 and other carriage, as herein set forth, of a spring propelling apparatus consisting of the stationary shaft *a*, spring *b*, spring-barrel and winding-drum *d*, and the cord *e*, said cord being connected with the winding-drum *d* and the 90 driving-axle *f*, substantially as described.

2. The spring-barrel *d*, fitted loosely on the stationary shaft and containing the spring *b*, having its ends attached respectively to the stationary shaft and the barrel, and said barrel being a winding-drum, and having the driv- 95

ing cord *e* connected with it and the driving-
axle of a toy locomotive or other vehicle such
as herein set forth, substantially as described.

3. The combination, in a toy locomotive or
other vehicle, as herein set forth, of driving
mechanism constructed and arranged substan-
tially as herein described, and spring-brakes
arranged with the axle, substantially as de-
scribed.

4. The combination, with the driving-axle
of a toy locomotive or other vehicle, as herein

set forth, of coiled-spring brakes *j*, substan-
tially as described.

In witness whereof we have hereunto signed
our names in the presence of two subscribing 15
witnesses.

CHARLES F. RITCHEL.
JEREMIAH STEVER.
